CLAIM

The ornamental design for a “light bulb” as shown and described.

DESCRIPTION

FIG. 1 is a perspective view showing my design;
 FIG. 2 is another perspective view thereof;
 FIG. 3 is a front elevational view thereof;
 FIG. 4 is a rear elevational view thereof;
 FIG. 5 is a right side elevational view thereof;
 FIG. 6 is a left side elevational view thereof;
 FIG. 7 is a bottom plan view thereof; and,
 FIG. 8 is a top plan view thereof.
 The broken lines in the drawings illustrate portions of the light bulb that form no part of the claimed design.
